UNITED STATES PATENT OFFICE.

TREVOR C. LEUTZE, OF MORTON, PENNSYLVANIA.

HAIR-PIN.

1,039,762.

Specification of Letters Patent.

Patented Oct. 1, 1912.

Application filed May 3, 1912. Serial No. 694,945.

To all whom it may concern:

Be it known that I, TREVOR C. LEUTZE, a citizen of the United States, residing at Morton, in the county of Delaware and State of Pennsylvania, have invented certain new and useful Improvements in Hair-Pins, of which the following is a specification.

In the operation of dressing the hair, it is necessary to have hair pins to hold the hair in place. The present style of hair pin is plainly visible. My invention is directed to providing a hair pin that will have the top of the hair pin covered with hair, either natural or artificial, made in various shades, so that all hair can be matched. This hair on the pin makes the latter invisible and also aids in making the pin hold more firmly in the hair.

Figure 1 shows the hair pin; the position of the hair being shown by the dotted line and the neck upon which it is wound by the solid line within the dotted line. Fig. 2 shows the hair pin complete, the hair having been wrapped around the neck to form the top of the pin. Fig. 3 shows perspective view of a shank, neck—the latter cut through crosswise at about the center of its curve—and the shoulder.

The shank 4 of the hair pin is made of bone, celluloid, metal or other material suitable for hair pins. It can be made of any suitable or desirable shape. At the upper end of the shank is a shoulder 3. Beyond this shoulder is the neck 1. The portion of this neck adjacent to the shoulder is of less circumference than the shoulder. Over this neck is wound the hair 2. The shoulder ordinarily will be formed by simply continuing the shank of its regular circumference to its upper end and having the neck extend from this upper end with a less circumference than the shank. The shank in such a construction usually tapers to the point from some point on its length, and from that point to its upper end is substantially the same diameter. By this construction the hair pin will slide into the hair very readily as there is no projecting shoulder to be pushed into the hair. I wrap the hair 2 around the neck 1 making the end of the wrapping of hair to lie close to the shoulder 3. I make the hair layers thick enough to

fill out the neck sufficiently to make the top of the desired size. 55

In practice it is usually most convenient to wrap the neck so that the top of the hair pin where it joins the shank will be of the same circumference and shape as the latter to avoid catching in the hair, and making 60 the rest of the top according to the esthetic requirements. The hair can be natural or artificial. An excellent effect is obtained with cheapness by making the lower layers of artificial hair and the upper layers of 65 natural hair.

The hair pins can be furnished complete to the purchaser with a wrapping either of natural or of artificial hair which is not quite of the desired thickness, upon which 70 can be wound a few wisps of her own hair, thus insuring a perfect match, the hair underneath matching approximately the wisp wound upon it. Frequently an excellent effect is obtained by making the outer hair 75 layers slightly loose and fluffy.

The shoulders 3—3 against which the hair is wound hold it firmly in position. By having the hair covered top of the hair pin for a portion of its length substantially on 80 a line with the shank the top can be pushed partly into the hair of the head and the friction between the hair on the head and the hair on the top of the pin will hold the pin very firmly in place. My improvement 85 is capable of use in any size of hair pin.

The hair pin is used in the same way as an ordinary hair pin, but it need not be pushed under the hair nor be hidden in any way, as it will be substantially invisible. 90

I claim—

A hair pin having a shank and a neck formed at the end of the shank of less circumference than the shank and joined to the shank, a shoulder at the junction of the 95 neck and shank, and a wrapping of hair around the neck fitting against the shoulder and filling up the neck to form a hair pin top of the desired size.

In testimony whereof I affix my signature 100 in presence of two witnesses.

TREVOR C. LEUTZE.
